CLAIM

The ornamental design for a lower front fascia skid plate, as shown and described.

DESCRIPTION

FIG. 1 is a front perspective view of a lower front fascia skid plate showing our new design;

FIG. 2 is a top view thereof;

FIG. 3 is a bottom view thereof;

FIG. 4 is a front view thereof;

FIG. 5 is a rear view thereof; and,

FIG. 6 is a side view thereof.

It will be understood that the broken lines shown in the drawings illustrate portions of the lower front fascia skid plate that form no part of the claimed design.

1 Claim, 6 Drawing Sheets
